IGNITION SYSTEM

Arthur W. Robinson, Jr., Schenectady, N. Y., assignor to General Electric Company, a corporation of New York

Application November 26, 1942, Serial No. 467,063

8 Claims. (Cl. 315—213)

My invention relates to ignition systems and more particularly to such systems as are conventionally known as low tension systems.

An object of my invention is to provide an improved ignition system.

Another object of my invention is to provide an improved low tension ignition system wherein the use of a spark gap or a tube circuit is not required to provide the desired exciting current to a spark plug transformer.

A further object of my invention is to provide an improved electrical ignition system for providing an intermittent or periodically varying relatively high rate of change of output current responsive to a predetermined periodic or intermittent function of the system.

Further objects and advantages of my invention will be better understood from the following description referring to the accompanying drawing, and the features of novelty which characterize my invention will be pointed out with particularity in the claims annexed to and forming part of this specification.

The drawing schematically illustrates an ignition system provided with an embodiment of my invention applied to an engine ignition system, although the general arrangement can be used in other ignition systems such as are used for burners.

Referring to the drawing, I have shown as a source of electrical power supply a magneto having a relatively stationary core 10 and a rotatable inducing magnet 11 mounted on a shaft 12 adapted to be driven at a predetermined desired speed relative to the periodic or intermittent discharges of ignition spark discharge plugs connected to the system. In this type electrical system, the source of electrical power connected to the supply circuit should have a varying characteristic such as a periodically varying alternating or intermittent voltage or current, and in the illustrated system, a periodic or intermittently varying current is induced in a magneto coil 13 by the magnetic variations produced in the core 10 by the rotation of the exciting magnet 11. The magneto coil 13 is adapted to be short-circuited by a circuit breaker including a relatively stationary contact 14 and a movable contactor element 15 connected across the coil 13. The contactor 15 is arranged to be operated in a predetermined relationship relative to the position of the magneto exciting magnet 11 by an operating cam 16 which is operated at a speed bearing a predetermined relationship to the speed of operation of the magneto exciting magnet 11, such that the circuit breaker is opened substantially at the time that the largest current is induced in the coil 13. Two circuits are connected in parallel across the terminals of the coil 13 and across the circuit breaker contacts 14 and 15. One of

these parallel circuits includes a condenser 17 and the other parallel circuit includes a magnetically saturable reactor 18 connected in series with a rotatable terminal arm 19 of a distributor 5 which is arranged to be operated at a predetermined speed relative to the speed of the engine to contact other terminals 20 of the distributor in a predetermined sequence. Each distributor contact terminal 20 is connected to one terminal of a corresponding spark plug transformer primary winding 21, and the other terminal of each of the transformer primary windings 21 is connected to ground 22, to the other side of the condenser 17, circuit breaker contactor 15, and magneto coil 13. Each transformer is provided with a secondary winding 23 which is connected across the electrodes 24 of a spark plug 25. The spark plugs are periodically or intermittently energized at a predetermined periodic or intermittent rate depending on the speed of the engine and the corresponding operation of the magneto magnet 11, the cam 16, and the distributor terminal contact arm 19, which are all arranged to operate at a predetermined speed relative to the speed of the engine to which the spark plugs 25 are arranged to provide ignition. Thus, when the current induced in the magneto coil 13 substantially reaches its maximum value, the cam 16 is operated to a position which opens the contacts 14 and 15 of the circuit breaker, thereby impressing the relatively high intermittent or periodic voltage across the above-mentioned parallel circuit. The branch of this parallel circuit including the saturable reactor 18 is adapted to form a complete circuit by operation of the distributor contact arm 19 into electrical contact with a contact terminal 20, but since the saturable reactor offers a relatively high impedance to the flow of electric current therethrough when it is substantially 20 unsaturated, relatively little current passes through this branch of the parallel circuit, and a relatively high charge passes into the condenser 17. As current passes through the saturable reactor 18, it becomes substantially magnetically saturated and offers a relatively low impedance to the passage of current therethrough, such that the condenser 17 subsequently discharges through the reactor 18 and through a primary winding 21 of one of the spark plug 25 transformers. This provides a periodically varying high output current having a relatively high rate of change to the output circuit which includes the reactor 18, distributor contact arm 19, distributor contact 20, and transformer primary winding 21, thereby inducing a relatively high voltage in the corresponding transformer secondary winding 23 and across electrodes 24 of a spark discharge device 25 and produces the desired electrical discharge across these electrodes.

While I have illustrated and described a par-

ticular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent in the United States is:

1. An electrical system including a source of electrical power supply, a circuit breaker connected across said source of electrical power supply, means for periodically operating said circuit breaker, an electrical output circuit, means including a condenser connected across said source of electrical power supply and a saturable reactor connected in series with one side of said condenser and one side of said output circuit for providing a periodically high output current to said output circuit responsive to the periodic operation of said circuit breaker, and means for connecting the other side of said output circuit to the other side of said condenser.

2. An ignition system including an output circuit, a condenser, means for connecting one side of said condenser to one side of said output circuit, a saturable reactor connected in series with the other side of said condenser and the other side of said output circuit, and means including an intermittent voltage source of electrical power supply applied across said condenser for providing an intermittent high output current to said output circuit responsive to said intermittent voltage and the subsequent intermittent discharges of said condenser through said reactor on substantial magnetic saturation of said reactor.

3. An ignition system including an output circuit, a condenser, means for connecting one side of said condenser to one side of said output circuit, a saturable reactor connected in series with the other side of said condenser and the other side of said output circuit, and means including an alternating current supply circuit connected across said condenser for providing an alternating high output current to said output circuit responsive to said alternating current and the subsequent discharges of said condenser through said reactor on substantial magnetic saturation of said reactor.

4. An ignition system including an output circuit, a condenser, means for connecting one side of said condenser to one side of said output circuit, a saturable reactor connected in series with the other side of said condenser and the other side of said output circuit, means including an intermittent voltage source of electrical power supply applied across said condenser for providing an intermittent high output current to said output circuit responsive to said intermittent voltage and the subsequent intermittent discharges of said condenser through said reactor on substantial magnetic saturation of said reactor, an ignition spark discharge device, and means for connecting said spark discharge device to said output circuit.

5. An ignition system including a source of electrical power supply, a circuit breaker connected across said source of electrical power supply, means for periodically operating said circuit breaker, an electrical output circuit, means including a condenser connected across said source of electrical power supply and a saturable reactor connected in series with one side of said

condenser and one side of said output circuit for providing a periodically high output current to said output circuit responsive to the periodic operation of said circuit breaker, means for connecting the other side of said output circuit to the other side of said condenser, an ignition spark discharge device, and means for connecting said spark discharge device to said output circuit.

6. An ignition system including a source of electrical power supply, a circuit breaker connected across said source of electrical power supply, means for periodically operating said circuit breaker, a transformer having a primary winding and a secondary winding, means for connecting one terminal of said transformer primary winding to one side of said source of electrical power supply, and means including a condenser connected across said source of electrical power supply and a saturable reactor connected in series to the other terminal of said transformer primary winding and the other side of said source of electrical power supply for providing a periodically high output current through said transformer primary winding responsive to the periodic operation of said circuit breaker and the subsequent periodic discharge of said condenser through said reactor on substantial magnetic saturation of said reactor.

7. An ignition system including a source of electrical power supply, a circuit breaker connected across said source of electrical power supply, means for periodically operating said circuit breaker, an ignition circuit distributor, a transformer having a primary winding and a secondary winding, means for connecting said distributor in series with one terminal of said transformer primary winding, means for connecting the other terminal of said transformer primary winding to one side of said source of electrical power supply, and means including a condenser connected across said source of electrical power supply and a saturable reactor connected in series to the other side of said distributor and the other side of said source of electrical power supply for providing a periodically high output current through said transformer primary winding responsive to the periodic operation of said circuit breaker and the periodic discharge of said condenser through said reactor on substantial magnetic saturation of said reactor.

8. An ignition system including a magneto providing a source of electrical power supply, a circuit breaker connected across said source of electrical power supply, means for periodically operating said circuit breaker, a transformer having a primary winding and a secondary winding, means for connecting one terminal of said transformer primary winding to one side of said source of electrical power supply, means including a condenser connected across said source of electrical power supply and a saturable reactor connected in series to the other terminal of said transformer primary winding and the other side of said source of electrical power supply for providing a periodically high output current through said transformer primary winding responsive to the periodic operation of said circuit breaker and the subsequent periodic discharge of said condenser through said reactor on substantial magnetic saturation of said reactor, an ignition spark discharge device, and means for connecting said spark discharge device to said transformer secondary winding.

ARTHUR W. ROBINSON, JR.
